AUTOMATIC INTERNAL GRINDING
MACHINE

Karl Jung, Berlin, Germany

Application January 29, 1936, Serial No. 61,383
In Germany March 28, 1935

10 Claims. (Cl. 51—233)

In internal grinding machines, in which the feed and cross-feed of the grinding wheel, the grinding motion and the operation of truing the grinding wheel have to be controlled automatically as soon as the work has been clamped and the machine has been set in motion, that is to say, in the case of so-called automatic internal grinding machines, the control of the various operations has been effected heretofore hydraulically or electrically. Neither of these two methods of control functions absolutely satisfactorily. In the case of electrical control, accurate operation of the contacts cannot be attained, and likewise in the case of hydraulic control in machines of high output, accurate reversing operations cannot be attained.

According to the invention an automatic internal grinding machine, in which the position of all the parts at the end of each cycle of working operations is the same as the position at the commencement of the working cycle, is characterized in that for carrying out all the control movement for the feed of the tool, work and truing tool, cams, cam discs or the like are employed, which cams, cam discs or the like are driven by a cam shaft which makes one complete revolution during one working cycle, while the actual feed movements are carried out by any mechanical, hydraulic or the like gears, said cam shaft being turned by two means each driving it during a part of each revolution.

Thereby the disadvantage of the existing methods of automatic control for such machines is obviated and the control operations are effected in absolute dependence upon one another and in absolutely the correct sequence and directly one after the other so that high outputs can be ensured in the shortest conceivable time.

The accompanying drawings show diagrammatically by way of constructional example the driving device of an internal grinding machine according to the invention in which Figs. 1a and 1b together is a diagrammatic view of the entire machine, and Fig. 2 is a side view of a detail.

In the drawings 1 is the reciprocating table of an internal grinding machine on which is mounted in known manner the device for receiving and driving the work to be ground. This table is reciprocated hydraulically, namely by a piston 2 moving in a cylinder 3. The piston rod 2a is connected to the table 1 by means of an intermediate member 2b.

For reversal, there are provided on the table 55 stops 4 and 5 adjustable in the longitudinal di-

rection of the table, which stops abut against a butt strap 6. The latter is mounted in a lever 7, 7a, adapted to rock about a pin 7b. The arm 7a is constructed in known manner as a knife-edge and co-operates with a roof-shaped lever 8 to produce complete reversal after the commencement of the feed operation. The roof-shaped lever 8 is under the influence of a spring.

The oil pressure for the hydraulic piston 2 is produced by a pump 9 which is set in rotation in any desired manner, not shown in the drawings, off the main drive of the machine. The oil is pumped past a pressure-relief valve 10 into a conduit 11, which opens into the casing of a change-over valve 12. The change-over valve 12 is in the form of a piston valve and operates so that, according to the position of the piston, the recess provided in the piston connects the conduit 11 alternately with the conduit 13 or with a conduit 16. A spring 119 holds the valve in the position shown in the drawings in which the oil under pressure flows to the conduit 13. The conduit 13 opens into the cylindrical chamber of a throttle valve 14 which is likewise in the form of a piston valve and by means of which the quantity of oil under pressure which can flow through the conduit 13 and to the conduit 15 may be regulated; the valve 14 is illustrated in the closed position and the manner of its actuation will be described thereafter. Connected to the conduit 15 is a reversing valve 16 which, in the position shown in the drawings, connects the conduit 15 with the conduit 17, which leads to one side of the cylinder 3 and when it is reversed brings the conduit 15 into communication with the conduit 18 which leads to the second side of the cylinder 3. The conduit 17 or 18 which in each case is not in communication with the conduit 15, is connected by the reversing valve 16 to a discharge conduit 19 which returns the oil under pressure to the oil tank 20.

For driving the automatic feed device there is a further hydraulic mechanism to which oil is supplied by a pump 21, preferably mounted on the same shaft 21a as the pump 9. Both pumps 9 and 21 draw from the oil tank 20 and the oil from the pump 21 is conveyed by a conduit 22 to the gear box 23, which is merely indicated in the drawings by its outline. Connected in front thereof is a stopping and starting valve 24 and the latter, in the position shown in the drawings, in which it is held against the action of the spring 96, connects the supply conduit 22 with the gear box. If the spring 96 can operate and change over the valve, the conduit 22 is

then in communication with the conduit 25 which returns the oil to the oil tank 20 by a conduit not shown in the drawings. The oil under pressure passing through the gear box is returned to the oil tank through the conduit 25a.

The hydraulic gear 23 rocks an arm 26 to and fro in known manner. The said arm is connected by a link 27 to a pawl lever 28 of a ratchet device, so that upon the reciprocation of the arm 26, the ratchet wheel 28a together with the shaft 28b on which the ratchet wheel is mounted is rotated. The shaft 28b acting through three gear wheels 29 drives the shaft 30 on which are mounted all the cams necessary for the automatic control. These control cams are denoted by 31-37. The end of the shaft 30 is connected by bevel gears 38 to a shaft 39 which in its turn drives a shaft 41 through bevel wheels 40. Mounted on the said shaft 41 is a cam 41a which controls the cross-feed of the grinding wheel. The mounting of the grinding wheel and the method of its cross-feed may be as desired. In the constructional example, it is assumed that the grinding wheel 25 is suspended in a cradle, the movement of the cradle being controlled by the cam 41a in a similar manner to that described in my U. S. Patent No. 1,975,899.

During one revolution of the shaft 30, complete machining of an article is effected. The rotation of the shaft 30 during one part of the working operation is effected by the ratchet mechanism 26-28 off the driving gear 23 which regulates the cross-feed of the grinding wheel. During another part of the revolution, on the contrary, rotation of the shaft 30 is effected off the reciprocating table 1. Those working operations which are closely connected with the cross-feed of the grinding wheel, namely roughing and finishing are carried out in agreement with the cross-feed of the grinding wheel, while the other working operations, that is to say, the truing of the grinding wheel and the exchange of the work are dependent upon the position of the table 1 and consequently must be controlled in close relationship with the table movement.

For rotating the shaft 30 by the table 1, a roof-shaped cam 42 is provided on the latter, the said stop being adapted to co-operate with a roller 43. As long as the work is being machined, the table 1 reciprocates in the usual manner, being actuated by the hydraulic gear 2, 3, reversal taking place by rocking of the lever 7 which is connected to the stop 6 and which of course reciprocates the reversing valve 16. As soon as machining is completed, the strap 6 is removed out of the path of the stop 5. After the stop 5 has passed by, the strap is again lowered so as to come into contact with the stop 118. This takes place by means of the cam 32. This cam and also the other cams 34-37 have been shown in the drawings merely as circles. The shapes which these cams must have follow at once from their mode of operation. The cam 32, therefore, at the moment at which the machining of the work is completed must have a descending part, so that the nose of the bell-crank lever 48 can drop in. The bell-crank lever consequently moves under the action of a spring 49 in the clockwise direction, it draws the rod 50 with it and thereby rotates an eccentric 51 mounted on the pin 1b. Bearing against this eccentric 51 is a rod 52 which is carried on the upper arm 7 of the bell-crank lever and has its upper end pivoted

to the stop 6. By the raising of the rod 52, the stop 6 is moved so that it no longer lies in the path of the stop 5. As soon as the stop 6 has been lifted up, therefore, the table can continue to run to the left, the cam 42 thereby coming into engagement with the roller 43. The double lever 43a carrying the roller 43 is thereby rocked so that the pull rod 53 is raised against the action of the spring 53a carrying with it the pawl 54 which engages the ratchet wheel 33 on the shaft 30, so that the shaft 30 is thereby rotated further by a certain amount in accordance with the movement of the table. The ratchet wheel 33 has four tooth gaps denoted by I-IV. According to the position of the shaft 30, the pawl 54 at the moment at which the table effects the rotation of the shaft 30, always engages one of these tooth gaps, thereby rotating the shaft 30 through a certain amount. During one revolution, therefore, a rotary movement of the shaft 30 is effected four times by the table.

Provided on the table 1 are two further cams 44 and 46 co-operating with rollers 45 and 47. The cams 42, 44 and 46 and the corresponding rollers lie in different vertical planes so that they do not interfere with each other in their operation. When after the stop 6 has been rendered inoperative, the table moves to the left in the drawings, the cam 42, as already mentioned, will have first become operative. A length of time later, namely at the end of the left-hand stroke the cam 44 becomes operative and then rocks the bell-crank lever 45a carrying the roller 45 in an anti-clockwise direction. The said lever is held by a spring 67 in abutment with a stop pin. Pivoted about a pin 65 on the end of the second lever arm of the bell-crank lever 45a is a rod 55. The latter is held by a spring 55a against a stop pin in the position shown in the drawings, in which a nose 60 provided on the rod 55 is situated behind the upper end of a lever 59. The latter is pivoted at 61 to a double lever 58, the second arm whereof is connected by a link 57 to the cam lever 56. The said cam lever which is held in the operative position by a spring 116 bears against the cam 31. As long as the lever 58 is stationary, the pin 61 of the rod 59 serves as pivoting point. Consequently, if due to the action of the cam 44 the rod 55 makes a movement to the right in the drawings, it rocks the rod 59 in a clockwise direction. The rod 62, which is connected to the rod 59, is thereby also moved and the latter abuts against a valve 63. This valve which is normally held closed by a spring 66, is situated in the conduit 17 leading to the left-hand side of the cylinder 3. The opening of the valve 63 renders the conduit 17 pressure-less because the oil flowing to it will now flow past the valve. The table consequently cannot begin its right-hand stroke and remains stationary in its outermost lefthand position. This position, in which the cam 44 lies above the roller 45, is that in which the work is exchanged. Shortly before this end position is reached the reversing valve 16 is shifted by means of a stop 121 in a manner hereinafter described.

For re-starting the machine after exchanging the work, there is provided a push knob 64, whereby the rod 55 can be lifted against the action of the spring 55a, so that its nose 60 releases the lever 59. Consequently, the valve 63 can close again under the action of the spring 66 and the working operation can commence. When the cam 44 releases the roller 45, the bell-

crank lever 45a under the action of the spring 67 can also return with the rod 55 into its initial position again, since the rear end of the nose 60 is bevelled, so that the rod 55 is lifted over the upper end of the rod 59.

5 In a certain position of the table 1 during its movement to the left the cam 46, as above described, comes into engagement with the roller 47 of a double lever, which thereby lifts the rod 68. The bell-crank lever 69 is thereby rotated, the said bell-crank lever being normally held by the spring 91 in abutment against a pin 92, and the abutment surface 70 of this lever swings outwardly to the left in the drawings. This abutment surface 70 co-acts with the abutment surface 71 of a rod 72. The said rod is pivoted by its second end to a double lever 75, the free end of which bears against the valve 12. In the vicinity of the pressure surface 71 of the rod 20 is pivoted a link 74, the lower end of which engages the cam lever 73. The cam lever 73 cooperates with the cam 37 and is held by a spring 73a against the said cam. The cam 37 is shaped so that the cam lever 73 can be set by it in two 25 different positions. In the one position, shown in drawings, it holds the abutment surface 71 below the path of the abutment surface 70 of the lever 69, and in the other position, that is to say, when the nose of the lever 73 can drop 30 into a recess of the cam 37, the abutment surface 71 comes in front of the abutment surface 70. When the abutment surfaces 70 and 71 are opposite to one another, the movement of the cam 46 over the roller 47 causes the rod 72 to 35 move to the left. The valve 12 is thereby thrown over against the action of the spring 119, and the pressure liquid pumped by the pump 9 no longer flows through the conduit 13 and 15 to the reversing valve 16, but through the conduit 16, 40 18 comprising a throttle valve 11 which may be adjusted by hand as desired. The liquid under pressure is therefore regulated by the throttle valve and by means of the device described the table speed otherwise provided during the working 45 operation is replaced by another speed, namely the lower speed necessary for truing the grinding wheel.

The link 74 is furthermore connected to a three-armed lever 79 adapted to rock about the point 80. During the upward movement of the link 74, the said lever makes a rotation in the clockwise direction, carrying with it the link 81, which is pivoted by its second end to a double lever 82 and this double lever in its turn lifts 50 the link 83 which is connected to its second arm and which is also connected to the rod 84 running in fixed guides and also raising the said rod. The said rod 84 forms an abutment for an arm 85 which is mounted on the same shaft 60 as a toothed sector 86. The toothed sector meshes with a further toothed sector on a second shaft carrying the truing device 87. When the rod 84 is raised and the abutment arm 85 comes into engagement with it, the arm with the 65 truing device is thereby erected and brought into the truing position in which, on the further movement of the table, it comes into contact with the grinding wheel. The truing device is mounted on the table 1 itself. During truing, 70 the grinding wheel must be fed forward in the radial direction somewhat. This feeding device is indicated in the drawings by a spindle 90, the connection of which with the grinding wheel is not shown in the drawings. Fuller explanation is 75 also not necessary since such feed slides moved

by spindles are common knowledge. Mounted on the spindle 90, which in the drawings is shown rotated through 90° from its actual position, is a ratchet wheel 89. Loose on the same shaft is also a pawl lever 89a which is connected by a link 88 to the third arm of the lever 79. Thus, the rocking of the three-armed lever 79 effects, in addition to the adjustment of the abutment 84, also the necessary feed of the grinding wheel for truing. After truing, the truing apparatus 10 87 is turned over again by a cam 93 fixed to the frame acting upon the surface 87a of the truing apparatus.

15 During the time in which the shaft 30 is rotated by the table through the medium of the ratchet wheel 33, the hydraulic gear must be stopped. This purpose is served by the cam 34 which engages a lever 94. The lever 94 is connected by the link 95 to the stop valve 24 for the gear, and when a suitable recess in the cam 20 34 arrives opposite the cam follower of the lever 94, the spring 96 reverses the valve 24 and the oil under pressure is shut off from the gear 23 and flows through the conduit 25a into the oil tank. The cam 34 is so adapted that it always stops 25 the gear in the manner described at the times at which the shaft 30 is to be moved by the table, while at other times it reverses the valve 24 again so that the shaft 30 can then be rotated by the gear 23 in the manner described hereinbefore. 30 The times during which the shaft is driven in one way or the other follow one upon the other.

The cams 35 and 36 serve for regulating the 35 table speed by adjusting the throttle valve 14. The latter is connected by a link to a lever 97. This lever may be rocked either about its end point 98 or about the pin 100 situated substantially in its centre. The said pin is eccentrically mounted. The eccentric is provided with a hand lever 99. By rocking the hand lever 99, the lever 40 97 is consequently swung about the end point 98. The valve 14 is thereby adjusted and therefore throttles more or less the liquid flowing to the cylinder 3.

In addition to this possibility of manual adjustment a further adjustment by the cams is also provided, and for this purpose, pivoted to the point 98 of the lever 97 is a link 107, attached to which is one arm 109 of a three-armed lever 50 adapted to rock about the point 110. The other two arms 108 and 108a of the said lever engage the cam 35, by which the lever is rocked at the suitable time. In doing so it carries with it the lever 97 and adjusts the throttle valve. Pivoted to the end point 106 of the link 107 is a rod 103, 55 the free end point of which is adjustable relatively to two stops 101 and 102. By the movement of the link 107 and hence also of the rod 103 to the right in the drawings, the rate of flow of liquid to the cylinder 3 is increased, i. e. the 60 throttle valve 14 is opened wider. The cam 35 is adapted to rock the lever until the rod 103 abuts against one of the stops 101 and 102. The stops are adjustable by hand.

The adjustment of the rod 103 relatively to one 65 or other of the stops is effected by the cam 36 which cooperates with a lever 104. The latter is connected by a link 105 with the rod 103. The cam 36 acts so that on changing over from one method of machining to the other, that is to say for example, on changing over from roughing to finishing and conversely, the rod 103 is adjusted relatively to the one or the other of the stops. The three-armed lever 108, 108a, 109 is 70 made in two parts, i. e. the arm 109 is connected 75

to the arms 108 and 108a by a friction coupling, so that independently of the stroke made by the cam 35, the rod can be arrested by the stop 101 or 102. In its left-hand end position, the lever 109 bears against a stop-pin 111.

5 The machine may also be operated by hand by rotating the hand-wheel 120. For this purpose, mounted parallel to the shaft 30 is a further shaft 112 adapted to be rotated by a handle 113. This 10 shaft carries a number of eccentrics 114 and a gear-wheel 115. The eccentrics 114 co-operate with projections or arms provided on the cam levers 56 and 73. One of the eccentrics acts directly on the lever 109. By rotating the shaft, 15 the cam levers are lifted off the cams or held out of action. The gear-wheel 115 meshes with a gear sector 117, which is connected to the pawl lever 54. By the rotation of the shaft 112, the pawl is lifted off the ratchet wheel by an abutment surface 118 fixed on said sector 117 and remains inoperative.

20 In this way, by rotation of the shaft 112, the cams (with the exception of cams 32, 36, 41a which are necessary even for the nonautomatic 25 working of the machine) are rendered inoperative and the machine can now be controlled by hand, i. e., worked non-automatically if desired, e. g., when carrying out an operation which will not be repeated.

25 30 The cam 34 may likewise be rendered inoperative, although this is not necessary nor are any means indicated in the drawings for this purpose. If the cam 34 is in the operative position during manual operation and the workman forgets to allow the table to travel to the end position, the cam acts upon the cock 24 by rotation of the shaft 30, and at the end of each machining 35 operation, i. e., rough grinding or finishing, the gear is automatically stopped.

35 40 The operation of the machine is consequently as follows:

45 At the commencement of the working operation, when a fresh work piece is to be mounted, the table is at rest in the left-hand position. The cam 44 has depressed the roller 45 and the valve 63 has been opened by the parts 55, 59, 62 in the manner described hereinbefore, so that the pump runs idle, since the reversing valve 16 is in the position in which the pressure fluid is fed 50 to the conduit 17.

55 After clamping the work in the work holder situated on the table 1 but not shown in the drawings, the machine is started by a pressure on the knob 64. The rod 55 releases the lever 59 so that the valve 63 can close again under the action of the spring 66 and the table now starts to run to the right, the cam 42 coming into contact with the roller 43 and pressing the latter downwardly. At this time the pawl 54 is within range of the 60 notch 1 of the locking cam 33. By the depression of the roller 43, the pawl lever 54 is rotated and thereby the shaft 30 is rotated by a certain amount. By this short rotation, the following control movements are carried out on the cams 65 mounted on the shaft 30.

70 The cam 31 does not make any control movement, but on the contrary the cam lever 56 remains in the previously existing position. The cam 32, shortly before the completion of the travel of the table for clamping the work, had a position in which the cam lever 48 was engaged. Consequently, the rods 50, 52 had rendered the stop 6 inoperative and the continued movement of the table 1 to the left had become possible. 75 Immediately thereupon, however, namely after

the stop 5 had passed the stop 6, the shaft 30 had rotated the cam lever 48 in the anticlockwise direction, thereby lowering the rod 52 and bringing the stop 6 into the operative position again. Now, during the movement of the table to the right, the said stop 6 lifts as it passes over the inclined surface of the stop 5 so that the lever is not displaced.

5 The cam 34, which previously was in a position in which the lever 94 was engaged and the valve 24 shut, is brought by the aforesaid short rotation of the shaft 30 into the position shown in the drawings, and thereby the flow of oil to the gear 23 is started. Therefore, directly after the rotation of the shaft 30 by the ratchet wheel 33, the hydraulic drive of the shaft 30 commences. The cam 35 moves the lever 109 and the rods 107, 103 connected therewith to the right towards the stop 102 situated at this time in the operative position. Consequently, the working 20 speed necessary for roughing is adjusted at the throttle valve 14. The adjustment of the rod 103 in front of the stop 102 has been effected by the cam 36 on the previous outward movement of the table with the finished work. The cam 37 25 during this said time has no control to carry out.

30 In the further movement of the table to the right which is now effected by the pressure oil delivered by the pump 9, machining of the work is effected, the stop 6 effecting the reversal of the 35 table in co-operation with the two stops 4 and 5, adjusted according to the length of the work to be machined. The first working operation is the roughing or preliminary grinding of the work. During this roughing, the grinding wheel must 40 be fed in to the work. This is effected by the hydraulic gear 23 acting through the parts 26, 27, 28, 29, 30, 38, 39, 40, 41, 41a. As soon as the roughing operation is completed, the cam 32 becomes operative, the lever 48 again swings out 45 in the clockwise direction and acting through the rods 50 and 52 moves the stop out of the path of the stops. Consequently, the table now travels to the left beyond its working position.

50 During this time, the lever 104 is lifted out of the recess of the cam 36, thereby rotating the rod 103 about its pivot 106 and rocking it into the position shown in the drawings in which it is opposite the finishing stop 101. The cam 35 and lever 109, which previously had moved the rod 103 so far to the left that it is free from the stops 101, 102 now brings the rod 103 into contact with the stop 101, thereby adjusting the throttle valve 14 to the speed necessary for finishing. Simultaneously, the cam 37 also has rotated until the lever 73 now drops into a recess in the cam, and thereby under the action of its spring 73a lifts the push rod 72 by means of the link 74 so that the abutment surface 71 is opposite the surface 70. If now the carriage travels to the left so far that the cam 46 comes into engagement with the roller 47, the rods 68, 69 will bring into operation the abutment surface 70 and the reversing valve 12 will be moved by the push rod 72 and the lever 75 so that the passage 13 is closed and the liquid from the pump 9 now proceeds through the passage 76 in accordance with the adjustment of the throttle screw 11. A table speed is now adjusted which is necessary for truing the wheel.

75 Simultaneously, the rods 73, 74 will have rotated the three-armed lever 79 and the latter through the medium of the rods 81, 82, 83 will have lifted the rod 84 so that on the continued movement of the table to the left, the stop 85 80

abuts against the stop 84 and the truing apparatus is erected. Simultaneously, the three-armed lever 79 by means of the ratchet wheel 89a will have rotated the cross-feed screw 90 for the grinding wheel, so that the latter is fed the necessary amount towards the truing diamond and now as the truing diamond passes the grinding wheel, the latter will be trued.

On the abutment of the cam 42 against the roller 43, the pawl lever 54 has again been rocked. The pawl of this lever has thereby come into engagement with the tooth II of the ratchet wheel 33 and by the movement of the pawl lever a further rotation of the shaft 30 has been effected by the arm 54. By this brief rotation of the shaft, the cam 32 is brought into the position in which the bell-crank lever 48 can again drop in, so that through the medium of the rods 50, 52, the stop 6 can again return to its initial position.

When after roughing the table moves to the left, the cam 31 rotates the lever 56 in the clockwise direction, so that the nose 60 is released from the lever 59 and the hydraulic table drive 25 remains in gear during truing and finishing. When the table moves further to the left, the truing device passes the grinding disc and trues it, and the movement to the left is continued until the stop 121 on cam 44 mounted on the 30 table comes into engagement with the stop 6 and thereby effects a reversal of the direction of travel of the table. As soon as the movement to the right has advanced so far that the diamond has released the grinding wheel again, the cam 35 46 also releases the roller 47 and the spring 91 pulls the lever 69 back and the spring 119 again throws over the valve 12, so that the table again travels at the normal speed. The cam 93 turns the truing device back into its inoperative position.

On the further movement, the cam 44 also releases the roller 45, while the cam 42 comes into engagement with the roller 43 and presses the latter downwardly. There thus takes place 45 another further movement of the shaft 30 by the pawl lever 54 which at this time is just within range of the notch III. The cam 34 is adapted so that whenever the shaft 30 is advanced by the ratchet wheel 33, the valve 24 is closed.

Upon the last-mentioned rotation of the shaft 50 30 by the ratchet tooth III, the lever 56 again runs on to the elevated part of the cam 31, so that the stop 59 is again moved in front of the nose 60. The cam 34 again throws over the valve 55 24, so that the drive is again effected by the gear 23.

The further cross-feed of the grinding spindle in the finishing operation which now commences is effected by the cross-feed gear 23. When the 60 extreme cross-feed position is attained, that is to say, when finishing is completed, the cam 32 again renders the stop 6 inoperative and in the meantime the notch IV has come within range of the pawl lever 54. The cam 34 now shuts off 65 the gear 23 again, the table runs to the left again, since the stop 6 is disengaged, and due to the cam 42 running on the roller 43, the shaft is rotated further through a certain amount by the pawl 54. The stop 6 is thereby released again and re- 70 turns into the operative position. The cam 35 draws the lever 109 back again so that it bears against the stop 111 and the cam 36 moves the rod 103 downwardly opposite the roughing stop 102. Upon the further movement of the table 75 to the left, first the stop 118 engages the stop 6

and shifts the reversing valve 16 to allow a movement of the table to the right and immediately thereupon the cam 44 comes into engagement with the roller, thereby disengaging the valve 63 through the medium of the rods 55, 59, 62 so that the machine stops. The completely machined work can now be removed and replaced by a fresh piece of work, whereupon machining of this fresh piece of work can be set in operation by pressure upon the knob 64.

The constructional execution of the machine is of course optional. Instead of the cam mechanism described it is also possible to employ link mechanism and likewise electrical or mechanical devices may be employed instead of the hydraulic 10 motors.

I claim:—

1. An automatic internal grinding machine comprising, in combination with mechanisms for carrying out the actual feed movements of the tool, the machine table carrying the work and the truing tool, cams adapted to carry out all the control movements for the said feed movements, a shaft driving the said cams, said cams being so devised that the position of all parts controlled 20 by them at the end of each working operation is exactly the same as at the commencement thereof, and two means adapted to turn said shaft for one complete revolution during one working operation, each means driving said shaft during a 25 part of each revolution.

2. An automatic internal grinding machine according to claim 1, and in which of the two means one is independent of the feeding movement of the machine table and serves for driving 35 the shaft during the machining operations (roughing, finishing) and the other is derived from the drive of the machine table and driving the shaft during the other operation, that is during truing and exchanging of the work.

3. An automatic internal grinding machine according to claim 1, and in which of the two means one is a hydraulic gear and serves for driving the shaft during the machining operations and also for cross-feeding the tool during machining and the other is derived from the drive of the machine table.

4. An automatic internal grinding machine according to claim 1, and in which of the two means one is a hydraulic gear and serves for driving the shaft during the machining operations and also for cross-feeding the tool during machining and the other is derived from the drive of the machine table, the hydraulic driving means of the cam shaft being rendered inoperative during the rotation of the latter by the means derived from the machine table.

5. An automatic internal grinding machine comprising, in combination with mechanisms for carrying out the actual feed movements of the tool, the machine table carrying the work, and the truing tool, six cams adapted to carry out all the control movements for the said feed movements, a starting and stopping device for the table movement controlled by one of the cams, a stop for controlling the reciprocatory movement of the table during the grinding process engaged and disengaged by a second of said cams, a driving means for a cam shaft, means for adjusting the working speed in accordance with the particular working operation controlled by a fourth of said cams, means for selecting the speed corresponding to the working process controlled by a fifth of said cams, means for engaging and disengaging a truing device, the truing speed and the feed 60 65 70 75 75

- of the grinding wheel for the purposes of truing controlled by a sixth of said cams, a shaft driving the said cams and means adapted to turn said shaft for one complete revolution during one working operation, said cams being so devised that the portion of all parts controlled by them at the end of each working operation is exactly the same as at the commencement thereof.
6. An automatic internal grinding machine comprising, in combination with mechanisms for carrying out the actual feed movements of the tool, the machine table carrying the work, and the truing tool, cams adapted to carry out all the control movements for the said feed movements, a shaft driving the said cams and means adapted to turn said last mentioned means comprising a ratchet wheel mechanism, and means for operating same, a cam connected with the table and setting said ratchet wheel mechanism in operation, and a driving means, said mechanism co-operating with the cam controlling the stopping of the driving means so that the pawl engages a ratchet tooth as soon as the latter driving means is stopped.
7. An automatic internal grinding machine according to claim 1, in which table stops are provided on the machine table and a butt strap engaged by said stops at the ends of each working movement thereby effecting the reversal of the table and on which a lever mechanism is ar-

ranged controlled by said shaft and adapted to bring said butt strap out of the path of the said stops.

8. An automatic internal grinding machine according to claim 1, in which a hydraulic drive is provided for the feed movement of the machine table, a liquid tank and a liquid supply for said drive, the said liquid supply comprising a reversing valve for adjusting the various speeds for the working operation and truing operation, a throttle valve for regulating the speeds for the various working operations, a reversing valve for the table movement and a cut-off valve by which the supply of oil is brought into communication with the liquid tank.

9. An automatic internal grinding machine according to claim 1, in which the control movement of the cams is effected by means of cam levers and means are provided adapted to lift said cam levers commonly off their cams thereby making them inoperative.

10. An automatic internal grinding machine according to claim 1, in which the control movement of the cams is effected by means of cam levers and means are provided adapted to lift said cam levers commonly off their cams thereby making them inoperative and further hand-operated means adapted to effect then the control of the machine by hand.

KARL JUNG. 30
